BURNER

Ronald S. Coulter, Roselle Park, N. J., and Alfred F. Schumann, Baltimore, Md., assignors to Hauck Manufacturing Company, Brooklyn, N. Y., a corporation of New York

Application June 18, 1936, Serial No. 85,854

5 Claims. (Cl. 158—76)

The invention relates to burning apparatus for combustible fluids such, for example, as fuel oil, and utilizing the kinetic energy of a gaseous medium such as air to effect atomization and mixing, the mixture being discharged for ignition in a highly atomized state through a tip of the burner provided with suitable orifices.

A burner, somewhat similar to the burner forming the subject matter of the present invention, and designed for mixing oil or other liquid fuel with a gaseous medium in two stages, is disclosed in a prior U. S. Patent #1,495,731 granted to applicants' assignee; and the same embodies means for altering the physical characteristics of the flame. It is an object of the present invention, while retaining the feature of two-stage mixing of liquid fuel with gaseous medium, to provide adjustment means whereby a predetermined ratio of primary to secondary outlets for gaseous medium is maintained; and, within the limits of the burner capacity, between the oil or other liquid fuel and the gaseous medium to be mixed therewith under constant inlet pressure of the latter, so as to maintain a constant velocity of gaseous medium across the fuel delivery member outlets irrespective of the quantity of fuel delivered.

A further object of the invention is to provide means for effecting simultaneous adjustment of a valve supplying fuel to the novel burner and the means for adjusting the supply of gaseous medium to be mixed therewith in the burner.

In carrying out the invention, an elongated casing is provided at its tip with a delivery opening, the said casing being further provided with an opening for receiving a gaseous medium. Mounted axially within the casing and terminating in proximity to its said delivery opening is a stationary nozzle member embodying circularly disposed radial outlets for delivery of fluid fuel; and about these openings is located an axially adjustable sleeve having peripheral ports to admit the gaseous medium to the interior of said sleeve. The latter is located between the casing and the outer end of the nozzle member, its periphery forming with the delivery end of the casing an annular and primary orifice, and its outer end being open and located in juxtaposition to the delivery opening of the casing.

Axial movement may be imparted to the said sleeve to vary the area of opening of the annular orifice; and this movement may be effected in accordance with the supply of fuel from a valve associated with the burner through intermediate mechanism linking the valve and burner controls

to each other. Within the sleeve a further annular and secondary orifice is formed about the stationary nozzle member adjacent its radial outlets and through which gaseous medium under constant pressure is delivered to afford constant velocity of the gaseous medium across the fuel ports or radial outlets irrespective of the position of the sleeve relative to the nozzle and casing, whereby the volume of fuel flow, within the fuel capacity of the burner, may be varied without affecting the degree of atomization and at the same time maintaining a predetermined proportion of gaseous medium to fuel.

The nature of the invention, however, will best be understood when described in connection with the accompanying drawings, in which:

Fig. 1 shows the novel burner and associated fuel valve in end elevation.

Fig. 2 is a side elevation thereof.

Fig. 3 is a longitudinal section through the burner and adjusting mechanism, with the associated fuel valve shown in elevation.

Fig. 4 is a fragmentary vertical section illustrating a modification in the adjusting means for the burner.

Referring to the drawings, the burner is shown to consist of a suitable elongated casing or body having a longitudinally disposed chamber 10 into which the atomizing gaseous medium, as air under requisite pressure, is to be supplied. The casing is provided with a removable tip 11 having the delivery outlet 12 located axially with respect to the casing.

Fitting coaxially within the body is the fuel supply nozzle 13 which extends from the rear of the casing to the outlet end thereof, terminating in a head 14 provided with radial outlets 15, the nozzle being bored axially through to these outlets and designed to connect, for example, through a pipe 16 or the like with a fuel supply valve 17 which may be rigidly attached to the top of the burner casing, as indicated.

Intermediate the casing and nozzle member and axially adjustable therein is a sleeve 20 having peripheral openings 21 to admit air from the interior of the casing to the interior of said sleeve and about the nozzle outlets 15, the sleeve extending beyond said outlets and being provided with an outlet 22 for mixed fuel and air. The said sleeve outlet 22 flares toward the delivery outlet 12 of the casing and terminates in juxtaposition thereto. The inner surface of this sleeve provides a constricted annular portion or throat 23 affording a secondary orifice about the neck of the nozzle, the surface immediately in advance of

and succeeding said constricted portion flaring in opposite directions.

The periphery of the said sleeve, furthermore, is separated from the casing and forms with the 5 delivery end thereof a tapering annular or primary orifice 24 contacting toward the outlet 12, which orifice may be varied in cross-sectional area in accordance with axial adjustment of the said sleeve, which, to this end, has a sliding 10 fit through the rear portion of the casing and about the inner end of the nozzle member. This adjustment or reciprocation of the sleeve may conveniently be effected by means of a stem or handle 25 extending from a collar 26 about the 15 end of the said sleeve opposite its outlet, the said sleeve being journaled to rotate and slide on a trunnion 10' fixed to the body. To effect its rotation, the collar carries a lower arm or lug 27 from which extends inwardly and parallel 20 to the axis of oscillation of the collar a pin 28. This pin in turn fits into a correspondingly disposed arm 29 projecting radially from a further collar 30 or indicator member bearing over a portion of its periphery graduations 31 located 25 in proximity to an indicator point or finger 32 secured to the casing. Thereby the oscillation or angular movement of the handle 25 may conveniently be read to afford a measure of the amount of opening of the fuel supply valve 17. 30 Collar 30 is fixed to the sleeve 20, as by means of a screw 33, so that rotation transmitted from the collar 26 through pin 28 and arm 29 will be correspondingly imparted to the said sleeve. The latter is to be advanced or retracted axially in 35 conformity with such oscillation, which at the same time controls the volume of fuel supplied, as hereinbefore set forth. To this end, a helical slot 35 is cut through a portion of the sleeve 20 about the trunnion 10', and from the latter 40 extends radially outwardly and into said slot a pin 36. By this expedient it becomes possible to advance and retract the sleeve without causing lateral displacement of the stem 25 which might be objectionable in the present embodiment, as the same is also to be connected with 45 valve 17 to operate the valve simultaneously with the adjustment of the said sleeve 20.

To effect this oscillation of the sleeve in conformity with the oil supplied, as from valve 17, the stem 40 of the latter may be connected to the stem 25 through a link 41 and arm 42, the latter being secured to the said stem 40. An adjustable swivel connection between the arm and link, as indicated by the screw 43, serves in the 50 initial setting of the fuel valve. Operating handle 25 may be extended above the valve, and when oscillated will operate both the valve and the burner sleeve 20 to increase or decrease the supply of fuel from the former and to slide the 55 end of the sleeve respectively away from or toward the outlet 12 of the burner.

In Fig. 4 a modification is indicated in connection with the sliding or axial adjustment of the sleeve 45 relatively to casing 46, and this 60 modification relates more especially to an embodiment not involving simultaneous control of both the fuel valve and said sleeve position. Thus, there is no connection provided from the operating handle 47 to a fuel supply means. The 65 collar 48 to which this handle is attached is, therefore, connected directly to the sleeve 45, as by means of a screw 49, to cause the sleeve to partake of its angular movement upon the trunnion 50. The sleeve, as in the previously described embodiment, is similarly provided with a

helical slot 51 receiving a pin 52 extending radially from the said trunnion, so that, as the collar 48 turns, the said sleeve will be correspondingly advanced or retracted axially along the trunnion 50. In this embodiment, handle 47 will, of course, follow also the axial displacement of the sleeve; but this is not objectionable since it is not connected to any other mechanism. A set screw 53 may be provided to pass through the collar and sleeve and bear upon the periphery 10 of trunnion 50 when the desired adjustment of the sleeve has been secured.

We claim:

1. A burner, comprising an elongated casing closed at the rear and open at the front to afford a delivery opening, said casing being provided with an intermediate unrestricted inlet opening for a gaseous medium, a stationary nozzle member longitudinally disposed within the casing and having in proximity to the delivery opening radial outlets for delivery of liquid fuel, a sleeve adjustably mounted coaxially about the nozzle member with a portion intermediate the casing and outlets of said nozzle member spaced from both to afford passageways between the casing and said sleeve and between the latter and the nozzle member, said sleeve having peripheral openings for admission of the gaseous medium to its interior, the construction and arrangement thus providing for flow thereof through both passageways and in all positions of said sleeve about the nozzle member outlets, and the periphery of said sleeve at the delivery end of the casing forming therewith an annular orifice for the discharge of the gaseous medium flowing about the sleeve, and means to adjust axially the said sleeve relatively to the nozzle member outlets and the casing.

2. A burner, comprising an elongated casing closed at the rear and open at the front to afford a delivery opening, said casing being provided with an intermediate unrestricted inlet opening for a gaseous medium, a stationary nozzle member longitudinally disposed within the casing and having in proximity to the delivery opening radial outlets for delivery of liquid fuel, a sleeve adjustably mounted coaxially about the nozzle member with a portion intermediate the casing and outlets of said nozzle member spaced from both to afford passageways between the casing and said sleeve and between the latter and the nozzle member, said sleeve having peripheral openings for admission of the gaseous medium to its interior, the construction and arrangement thus providing for flow thereof through both passageways and in all positions of said sleeve about the nozzle member outlets, and the periphery of said sleeve at the delivery end of the casing being tapered and forming therewith an annular variable orifice for the discharge of the gaseous medium flowing about the sleeve, and means to adjust axially the said sleeve relatively to the nozzle member outlets and the casing.

3. A burner, comprising an elongated casing closed at the rear and open at the front to afford a delivery opening, said casing being provided with an intermediate unrestricted inlet opening for a gaseous medium, a stationary nozzle member longitudinally disposed within the casing and having in proximity to the delivery opening radial outlets for delivery of liquid fuel, a sleeve adjustably mounted coaxially about the nozzle member with a portion intermediate the casing and outlets of said nozzle member spaced

from both to afford passageways between the casing and said sleeve and between the latter and the nozzle member, said sleeve having peripheral openings for admission of the gaseous medium to its interior, the construction and arrangement thus providing for flow thereof through both passageways and in all positions of said sleeve about the nozzle member outlets, and the periphery of said sleeve at the delivery 10 end of the casing forming therewith an annular orifice for the discharge of the gaseous medium flowing about the sleeve and its inner wall forming with the outlet portion of the nozzle member a variable annular orifice, and means to adjust axially the said sleeve relatively to the nozzle member outlets and the casing.

4. A burner, comprising an elongated casing closed at the rear and open at the front to afford a delivery opening, said casing being provided with an intermediate unrestricted inlet opening for a gaseous medium, a stationary nozzle member longitudinally disposed within the casing and having in proximity to the delivery opening radial outlets for delivery of liquid fuel, a sleeve adjustably mounted coaxially about the nozzle member with a portion intermediate the casing and outlets of said nozzle member spaced from both to afford passageways between the casing and said sleeve and between the latter and the nozzle member, said sleeve having peripheral openings for admission of the gaseous medium to its interior, the construction and arrangement thus providing for flow thereof through both passageways and in all positions of said sleeve about the nozzle member outlets, and the periphery of said sleeve at the delivery 25 end of the casing forming therewith an annular orifice for the discharge of the gaseous medium flowing about the sleeve, and means to adjust axially the said sleeve relatively to the nozzle member outlets and the casing; of a fuel valve 30 carried by the casing and in communication with the nozzle member, said valve including means for varying the flow of fuel therethrough to supply different volumes thereof to the burner; and means interconnecting the sleeve adjusting 35 means with the said means for varying the volume of fuel supplied by said valve.

ing a Venturi throat which defines with the outlet portion of the nozzle member an annular constricted orifice, and means to adjust axially the said sleeve relatively to the nozzle member outlets and the casing.

5. The combination with a burner, comprising an elongated casing closed at the rear and open at the front to afford a delivery opening, said casing being provided with an intermediate unrestricted inlet opening for a gaseous medium, a 10 stationary nozzle member longitudinally disposed within the casing and having in proximity to the delivery opening radial outlets for delivery of liquid fuel, a sleeve adjustably mounted coaxially about the nozzle member with a portion intermediate the casing and outlets of said nozzle member spaced from both to afford passageways between the casing and said sleeve and between the latter and the nozzle member, said sleeve having peripheral openings for admission of the 20 gaseous medium to its interior, the construction and arrangement thus providing for flow thereof through both passageways and in all positions of said sleeve about the nozzle member outlets, and the periphery of said sleeve at the delivery 25 end of the casing forming therewith an annular orifice for the discharge of the gaseous medium flowing about the sleeve, and means to adjust axially the said sleeve relatively to the nozzle member outlets and the casing; of a fuel valve 30 carried by the casing and in communication with the nozzle member, said valve including means for varying the flow of fuel therethrough to supply different volumes thereof to the burner; and means interconnecting the sleeve adjusting 35 means with the said means for varying the volume of fuel supplied by said valve.
